FREQUENCY MULTIPLIER

Jan A. Rajchman, Philadelphia, Pa., assignor to
 Radio Corporation of America, a corporation
 of Delaware

Application April 30, 1942, Serial No. 441,168

2 Claims. (Cl. 315—5)

1

This invention relates generally to frequency multipliers and particularly to apparatus in which frequency multiplication is obtained by control of an electron beam in a cathode ray tube whereby the frequency of a voltage impressed upon the deflecting elements of such a tube may be multiplied to any other desired frequency, harmonic or otherwise.

The invention is an improvement on the system described in U. S. Patent 2,083,904 granted to John Evans on July 13, 1937, in that the instant invention is adapted more efficiently to derive extremely high output frequencies. The invention has particular utility in the generation of ultra high frequencies where an economical system of satisfactory frequency stabilization is desired. It permits the use of a crystal controlled oscillator, or other generator, of a fundamental frequency which can be accurately regulated, and the development of oscillations of any desired multiple of the fundamental frequency. The desired factor of frequency multiplication is obtained by suitable design of one of the electrodes of a cathode ray tube. Likewise, the wave form of the multiplied frequency may be controlled by the design of the multiplying electrode.

The use of a cathode ray tube for frequency multiplication is highly desirable since the electron beam is substantially devoid of inertia and therefore enables the generation of extremely high output frequencies. Energy may be applied to the deflection elements of a cathode ray tube to produce a beam trace of any desired form and having any desired speed of rotation.

Among the objects of the invention are to provide an improved frequency multiplier of the cathode ray type in which any desired factor of multiplication may be obtained. Another object of the invention is to provide an improved frequency multiplier in which currents of considerable amplitude may be generated at ultra high frequency. Still another object of the invention is to provide improved means for stabilizing ultra high frequency currents.

The invention will be more clearly understood upon reference to the drawing in which Fig. 1 is a schematic diagram of a preferred embodiment of the invention, Figs. 2 and 3 are schematic diagrams of modifications of the invention, and Figs. 4 and 5 are plan views of apertures of different shapes which may be employed in the invention.

Referring to Fig. 1, a cathode ray tube having an envelope 1 includes an electron emissive cathode 5 and a heater 2 which is supplied with power

5 from the battery or other source 3, through a variable resistor 4. Electrons emitted from the cathode 5 are accelerated and focused by the anode 6, which is connected to a point on the voltage divider 13, connected across the source of high potential 14. A grid-aperture electrode 11, connected to a source of negative potential is disposed between the cathode and anode to confine the electron beam to useful proportions. Horizontal and vertical deflection elements 7 and 8 are connected to a source of phase quadrature currents which are derived from a source of oscillations 10 of the fundamental frequency to be multiplied. An accelerating electrode 12, which 10 is optional, is connected to a second positive point on the voltage divider 13. A disc shaped electrode 15, having a plurality of apertures 25 of predetermined size, shape and relative spacing, is placed in the path of the deflected electron beam in such a manner that the apertures interrupt the beam a predetermined number of times during each rotation of the beam by the deflecting voltages.

In order to converge the path of the interrupted rotating beam to a small cross sectional area, the electrostatic focusing elements 16, 17, and 18, which are connected respectively to proper points on the voltage divider 13, are disposed in axial relation with the electrode 15. The constantly interrupted beam is thereby focused through an aperture 22 of a cavity resonator electrode 19 to the small target electrode 21.

Suitable coupling means 20 are provided for deriving energy for the load circuit 23 from the resonant electrode 19, which may be in the form of a cavity resonator of the type well known in ultra high frequency generators. The cavity resonator 19 and the target electrode 21 are connected to suitable biasing potentials from the voltage divider 12.

The invention has a distinct advantage over previously known devices in that the cavity resonator and target electrodes have extremely low capacitive coupling with respect to the other electrodes in the tube, thereby providing efficient operation at extremely high frequencies. The particular arrangement has the additional advantage that the A. C. component of the output frequency 45 may be derived from the coupling circuit 20, associated with the cavity resonator 19, and the D. C. component may be confined to the circuit 50 including the target electrode 21. If desired, a load 23' may be connected simultaneously with said load 23, for example, by opening the switch

24, in the circuit connecting the voltage divider 13 and the target electrode 21.

With the apparatus just described it is perfectly practicable to apply a stabilized frequency of, for example, 100 megacycles to the beam deflection elements 7 and 8. By providing 100 apertures in the electrode 15, it is possible to derive an output of 10,000 megacycles from the coupling circuit 20. If the frequency multiplication is of a low value, the resonant electrode may be omitted, and the output frequency derived directly from the target electrode 21.

Fig. 2 is a modification of the system described by reference to Fig. 1 in that a magnetic focusing element 26 is substituted for the electrostatic focusing elements 16, 17 and 18. A suitable source of power 27 is connected to the winding of the element 26.

Fig. 3 is a further modification of the system of Fig. 1 in that horizontal and vertical deflection elements 36 and 37 are substituted for the electrostatic focusing elements 16, 17 and 18, and so connected to the source of oscillations 10 that the original deflection of the beam is effectively neutralized, and the interrupted beam made to converge to the small cross-sectional area required for the small target electrode 21.

Figs. 4 and 5 are illustrative of the versatility of the invention in that various shapes and spacing of the apertures 25 in the electrode 15, may be combined with predetermined electron beam cross-sectional dimensions E', E'', which may be derived in any well known manner, to

provide desired wave shape for the output frequency. Heretofore, the control of the wave shape of currents of ultra-high frequency has frequently involved a serious loss in efficiency. This disadvantage is substantially reduced with the system described. Of course, if the output frequency is extremely high, considerable difficulty may be encountered in coupling efficiently to the cavity resonator 19 insofar as harmonic components of the output frequency are concerned.

I claim as my invention:

1. A signal frequency multiplier including a cathode ray device having means for generating an electron beam, an electrode having a plurality of apertures in the path of said beam, beam deflecting means responsive to said signal for scanning said apertures, a relatively small target electrode, a cavity resonator disposed between said apertured electrode and said target electrode, means for converging and directing said beam from said apertured electrode through said cavity resonator to said target electrode, means for deriving energy from said cavity resonator in the form of alternating currents, and additional means for simultaneously deriving energy from said target electrode in the form of pulsating direct currents.

2. Apparatus as claimed in claim 1 wherein said apertures in said apertured electrode are substantially square in shape and wherein said beam is directed diagonally across each of said apertures.

JAN A. RAJCHMAN.
